(57) **CLAIM**

The ornamental design for a flashlight style pipe, as shown and described.

DESCRIPTION

FIG. 1 is an exploded perspective view of the flashlight style pipe of the present invention with parts separated in line.

FIG. 2 is a perspective view of the flashlight style pipe of the present invention with the head (bowl) facing forward.

FIG. 3 is a perspective view of the flashlight style pipe of the present invention with head (bowl) facing away.

FIG. 4 is an exploded perspective view of the flashlight style pipe of the present invention with the head (bowl) facing forward, removed in alignment.

FIG. 5 is an exploded, perspective view of the flashlight style pipe of the present invention with the head (bowl) in alignment to be screwed into position as the bowl of the pipe.

FIG. 6 is an exploded, perspective view of the flashlight style pipe of the present invention with the bowl threaded into position for use as the bowl of the pipe and the cap of the bowl detached.

FIG. 7 presents an exploded, perspective view of the flashlight style pipe of the present invention with the bowl in place and with the cap in position to be threaded into place as the stopper of the pipe barrel.

FIG. 8 is a perspective view of the flashlight style pipe of the present invention with the pipe having all parts in place for use as a pipe.

FIG. 9 is a front elevation view of the flashlight style pipe.

FIG. 10 is a rear elevation view of the flashlight style pipe.

FIG. 11 is a bottom plan view of the flashlight style pipe.

FIG. 12 is a top plan view of the flashlight style pipe; and,

FIG. 13 presents an exploded, side elevation of all of the parts of the flashlight style pipe of the present invention.
